Primary Examiner — Paula Allen Greene(74) *Attorney, Agent, or Firm* — W&C IP(57) **CLAIM**

The ornamental design for an earphone, as shown and described.

DESCRIPTION

FIG. 1 is a front perspective view of an earphone; FIG. 2 is a rear perspective view of the earphone; FIG. 3 is a front elevational view of the earphone; FIG. 4 is a rear elevational view of the earphone; FIG. 5 is a top plan view of the earphone; FIG. 6 is a bottom plan view of the earphone; FIG. 7 is a left side elevational view of the earphone; and, FIG. 8 is a right side elevational view of the earphone. In the drawing the claimed design is defined by the shaded surfaces; the broken lines depict unclaimed environment that forms no part of the claimed design.

1 Claim, 8 Drawing Sheets(56)
